UNITED STATES PATENT OFFICE

164,389

WALL CLOCK

Raymond L. Smith, Arlington, Va.

Application June 26, 1951, Serial No. 15,669

Term of patent 14 years

(Cl. D42—7)

To all whom it may concern:

Be it known that I, Raymond L. Smith, a citizen of the United States, residing at Arlington, in the county of Arlington and State of Virginia, have invented a new, original, and ornamental Design for a Wall Clock, of which the following is a specification, reference being had to the accompanying drawing, forming part thereof.

Fig. 1 is a front elevational view of a wall clock showing my new design; and

Fig. 2 is an edge elevational view thereof.

The essential features of my design are shown in full lines.

I claim:

The ornamental design for a wall clock, substantially as shown and described.

RAYMOND L. SMITH.
